UNITED STATES PATENT OFFICE.

WILLIAM A. ECKERT, OF BUFFALO, NEW YORK.

AUTOMOBILE SIGNAL.

Application filed February 1, 1924. Serial No. 690,033.

To all whom it may concern:

Be it known that I, WILLIAM A. ECKERT, a citizen of the United States, residing at Buffalo, in the county of Erie and State of New York, have invented a new and useful Improvement in Automobile Signals, of which the following is a specification.

This invention relates to an electric signal for automobiles and other vehicles for indicating the direction in which the driver intends to turn his car and it has for its objects the provision of a signal for this purpose which is simple and compact in construction, efficient in operation and capable of being readily dismembered and assembled for inspection, adjustment and repairs.

In the accompanying drawings:

Figure 1 is a front elevation of the signal embodying my improvements. Figure 2 is a vertical longitudinal section thereof taken on line 2—2, Fig. 3. Figure 3 is a horizontal section taken on line 3—3, Fig. 2. Figure 4 is a vertical cross section taken on line 4—4, Fig. 2. Figure 5 is a perspective view of one of the reflectors of the signal. Figure 6 is a similar view of one of the lamp bases. Figure 7 is a vertical transverse section taken on line 7—7, Fig. 2. Figure 8 is a diagram of the wiring showing the manner of installing my improved signal on opposite sides of the front and rear ends of an automobile. Figure 9 is a horizontal section of a modified form of my invention. Figure 10 is a vertical cross section of the same taken on line 10—10, Fig. 9. Figure 11 is a vertical longitudinal section taken on line 11—11, Fig. 9.

Similar characters of reference indicate like parts throughout the several views.

Referring to Figures 1—7, the numeral 20 represents the body of the housing or enclosing casing of the signal which is preferably constructed of sheet metal of horizontally elongated and oval form and having a rearwardly dished upright rear wall 21 and a flange 22 which projects forwardly from the margin of said wall. The central part of this housing body is comparatively deep while the opposite end parts thereof are tapered or inclined forwardly. Extending across the front side of the body of the housing is the vertical face plate 23 of the same which is also constructed of metal and provided on its margin with a rearwardly projecting flange 24 adapted to removably

fit around the flange of the body and to be detachably secured thereto by screws 25 preferably arranged at the opposite extremities of the housing as shown in Figures 1, 60 2 and 3. On opposite sides of the central part of the face plate the same is provided with two light openings 26, 26 each of which has preferably the shape of an arrow pointing outwardly. This housing is supported by means of an upright standard having a wide upper section arranged within the central part of the housing and a lower narrow section which is arranged below the housing and adapted to be secured to a part 27 of the automobile as a support, for instance the upper edge portion of the back rest of the rear seat of an automobile so that the signal casing is arranged within the auto compartment and its face is directed rearwardly and is close to the inner side of the rear window 28 of the car, as shown in Figure 4. The upper section of the supporting standard is U-shaped in horizontal section and has an upright web 29 which engages the inner side of the central part of the face plate and is secured thereto by rivets 30, or otherwise, and its upright flanges 31 project rearwardly from this web and terminate close to the rear wall of the housing, as shown in Figure 3. The lower section of the standard has a narrow plate 32 which extends from the lower edge of the web 29 downwardly through a recess 33 in the central part of the lower flange on the housing and projects below the latter and terminates in a forwardly projecting base flange 34 which is secured to a support on the auto by screws 35 or the like. 70 75 80 85 90 95 100 105

Arranged in front of the plate 32 of the lower part of the standard is a cap which is U-shaped in horizontal section and rests with its lower end on the base flange 34 and with its upper end against the underside of the housing body and engages the front edges of its flanges 36 with the front side of the lower standard plate 32 so that its web 37 is spaced from this plate and forms, with the same and its flanges 36, a conduit which communicates at its upper end with the interior of the housing through the recess 33 while its lower end communicates with an opening 38 in the base flange 34. The upper part of the standard plate 32 is provided on its opposite edges with guide lugs 70 which are arranged on the underside of the housing, as shown in Figures 1 and 2 and

serve to guide the housing on to the standard while assembling the same. The electrical wires 39 extend through the opening 38, the conduit formed by the plate 32, web 37 and flanges 36, and the recess 33 into the housing for supplying the incandescent electric lamps 40, 41 within the housing with current and illuminating the same. This conduit cap is provided at its lower edges 5 with retaining lugs 50 engaging with recesses 51 in the flange 34 while its upper end engages frictionally with the underside of the housing and thereby holds this cap in place. These lamps are mounted one above 10 the other on the upper part of the standard so that one lamp is arranged on one side of the standard and within one end compartment of the housing while the other lamp is arranged on the opposite side of the 15 standard and in the other end compartment of the housing. For this purpose the upright flanges 31 of the upper section of the standard are provided with horizontal guide slots 42, 43, which extend to the rear edges 20 of these flanges and are arranged one high and the other low, as shown in Figure 2. Arranged in the slots 42, 43, are two supporting blocks 44, 45, respectively, each of which is provided at its upper end and 25 lower edges with horizontal grooves 46, which slidably engage with the corresponding edges of one of the guide slots. Mounted horizontally in an opening 47 in each of these carrying blocks is a supported 30 sleeve or socket 48, the front and rear ends of which open into one of the compartments and the adjacent part of the upper standard section, respectively. In the rear part of each supporting sleeve and facing 35 the inner side of the standard is a lamp plug or base 49 having preferably two contact points 52 which connect with two of the conducting wires 39, and in the front end of this supporting sleeve is slipped one of 40 the lamps 40, 41, the rear end of which has two contact points 53 adapted to engage with those of the base 49 and thus complete the circuit through the lamp. By 45 thus mounting the lamps one above the other on the upper part of the standard the same can be arranged more compactly without interfering with each other, and it is also possible to provide ample room for 50 running the wires and connecting the same with the lamps. Within each lamp compartment and engaging with the inner side of the adjacent end portion of the face plate so as to cover the arrow-shaped sight 55 opening therein is a transparent pane 54 of glass or similar material which is preferably fitted with its top and bottom and outer end edge with a packing strip 55 of felt or the like to keep the same tight and prevent rattling. When either one of the 60 lamps is illuminated the light of the same

shines through the pane and the respective opening in the face plate and thus gives a signal in accordance with the shape of this sight opening which indicates the direction in which the driver intends to turn. The 70 inner side of the body is preferably coated with white enamel, nickel plated or otherwise treated to cause the same to act as a reflector whereby the light of the lamp is directed forwardly through the respective 75 pane and sight opening. As a further aid in the reflection of light from the lamp to cause the same to be distributed over the entire inner side of the respective lamp compartment an auxiliary reflector is employed 80 in each compartment which also serves as part of the means for holding the respective lamp in its operative position. In the preferred form each of these auxiliary reflectors is constructed of sheet metal in the 85 form of a cup which has the convex side of its bottom 56 engaging the outer side of one of the flanges or partitions 31 and has its concave side facing toward the corresponding end of the respective compartment. The front wall 57 of this cup engages with the inner side of the adjacent 90 part of the respective pane and serves to hold it in place, and it is provided with a horizontal slot 58 which registers with the shaft of the arrow-shaped sight opening in that part of the face plate so as not to obstruct the passage of light therethrough. One of these auxiliary reflectors is provided 95 in the lower part of its bottom with an opening 59 which receives the front end of the adjacent low lamp supporting sleeve or socket 48 while the bottom of the other auxiliary reflector is provided with a similar opening 59 on the upper part of its bottom for receiving the front end of the adjacent high lamp supporting sleeve or socket, as shown in Figure 2, whereby 100 these lamps are arranged at different elevations within these reflectors and the latter throw the light of the same in opposite directions across the lamp compartment. The inner sides of these auxiliary reflectors are either polished, white painted or enameled, nickel plated or otherwise rendered highly 105 reflectant so as to utilize the light of the lamps to the best advantage. 110 Each of these auxiliary reflectors is held in place on its supporting flange, partition or wall 31 by a headed screw 60 secured to the outer side of this flange and passing through a key-hole slot 61 in the bottom of the respective reflector, thereby permitting 115 the latter to be applied to and removed from this flange without removing the screw. Inasmuch as the front sides of these reflectors bear against the inner side of the window panes and the same also receive the lamp sockets these reflectors serve to retain 120 the panes and lamps in place. 130

When it is desired to renew the lamp or repair a broken pane the body of the housing is first moved away from the upper part of the standard after the screws 25 are removed, thereby rendering the inside of the housing accessible for this purpose.

In practice two of such electric signals are preferably mounted on the front and rear side of the vehicle, one facing forwardly and the other rearwardly and means are provided whereby either the corresponding right hand lamps or the corresponding left hand lamps may be lighted simultaneously. For this purpose the lamps of both signals may be electrically connected with an electric source 62 by two switches 63, 64, one of which controls the circuit through the right hand lamps of both signals and the other the circuit through the left hand signals, as shown in Figure 8.

When the signal is to be used outside of the compartment of an automobile the same may be organized as shown in Figures 9, 10 and 11. In this construction the relation of the standard to the face plate and body of the housing is reversed and the upper part of the standard is secured to the body of the housing by rivets 65 passing through the web 66 of the standard and the back of the housing, as shown in Figures 9 and 10, and the face plate is removable forwardly from the body upon removing the fastening screws 67, when access to the interior of the housing is desired.

In order to hold the panes of glass in place in this instance a clip 68 is removably secured to the central part of the inner side of the face plate so that the opposite ends of this clip overlap the inner side of the panes, as shown in Figures 9 and 11, and thereby secure these panes to the face plate so that the removal of the latter carries the panes with it. In other respects this construction is substantially like that shown in Figures 1-8.

The signal is very compact in construction, neat in appearance, effective in operation and readily accessible when any of its parts require attention.

I claim as my invention:

1. A signal of the character described comprising a housing, a partition arranged within the housing and provided with a slot,

a supporting block arranged in said slot, a tubular socket mounted on said block, an electric lamp mounted in said socket, and a reflector mounted on said partition and enclosing said lamp and provided with an opening which receives said socket.

2. A signal of the character described comprising a housing, a partition arranged within the housing and provided with a slot, a supporting block arranged in said slot, a tubular socket mounted on said block, an electric lamp mounted in said socket, a reflector mounted on said partition and enclosing said lamp and provided with an opening which receives said socket, and provided with a key-hole slot, and a headed screw arranged on said partition and engaging with said key-hole slot.

3. A signal of the character described comprising a housing having a body and a face plate on the front side of the body and provided with a sight opening of arrow form, a lamp arranged within the housing, and a reflector enclosing said lamp and having its front part provided with a slot which registers with the shaft of said arrow-shaped opening.

4. A signal of the character described comprising a housing having sight openings on its front side and a standard opening on its lower side, a standard extending through said standard opening and having its upper part arranged within the housing and constructed of U-shape, the web of which is secured to a part of the casing and the flanges of which extend across the interior of the housing and form partitions, and lamps mounted on said partitions.

5. A signal of the character described comprising a housing having sight openings on its front side and a standard opening on its lower side, a standard extending through said standard opening and having its upper part arranged within the housing and its lower part arranged below the housing and having the form of a plate which terminates in a base flange, and a U-shaped cap engaging its upper and lower ends with said housing and base flange and engaging its flanges with said plate.

In testimony whereof I affix my signature.

WILLIAM A. ECKERT.
